US00D830367S

(12) **United States Design Patent** (10) **Patent No.:** **US D830,367 S**
(45) **Date of Patent:** **** Oct. 9, 2018**

(54) **HAND STRAP**

(71) Applicant: **Getac Technology Corporation**,
Hsinchu County (TW)

(72) Inventor: **Chia-Wei Chang**, Taipei (TW)

(73) Assignee: **GETAC TECHNOLOGY
CORPORATION**, Hsinchu County
(TW)

(**) Term: **15 Years**

(21) Appl. No.: **29/623,117**

(22) Filed: **Oct. 23, 2017**

(51) LOC (11) Cl. **14-02**

(52) U.S. Cl.

USPC **D14/440**

(58) **Field of Classification Search**

USPC D14/440; 206/45.23, 320, 45.2;
361/679.55; 294/25; 224/218
CPC ... G06F 1/1628; G06F 1/1626; A47B 23/044;
H04B 1/3888; H05K 5/0217

Primary Examiner — Cynthia R Underwood

(74) Attorney, Agent, or Firm — Locke Lord LLP; Tim
Tingkang Xia, Esq.

(57) **CLAIM**

The ornamental design for a hand strap, as shown and
described.

DESCRIPTION

FIG. 1 is a perspective view of a hand strap showing the
claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view showing the hand strap
for use with a portable electronic device;

FIG. 9 is another perspective view showing the hand strap
for use with a portable electronic device; and,

FIG. 10 is another perspective view showing the hand strap
being extended to support a portable electronic device.

The broken lines are directed to environment and are for
illustrative purpose only; the broken lines form no part of the
claimed design.

1 Claim, 10 Drawing Sheets
